HYDRAULIC CHECKING HINGE

Henry S. Diebel, Downey, Calif., assignor to
G. G. Bakewell, Pasadena, Calif.

Application August 19, 1946; Serial No. 691,559.

6 Claims. (Cl. 16—54)

1

This invention relates to an hydraulic door checking hinge.

One object of the invention is to provide a hinged door checking mechanism. Another object is to provide a hinge for a hand-operated door which controls the relative rates of movement of the door throughout its movement. Another object is to provide interchangeable by-pass units for use in an hydraulic checking hinge. These and other objects are attained by my invention which will be described below, and will be understood from the description and the accompanying drawings in which:

Fig. 1 is a cross-sectional view partly in section showing a preferred form of the hydraulic checking hinge of my invention.

Fig. 2 is a top view of my checking hinge, showing the attachment of the hinge leaves to a door and to a doorframe;

Fig. 3 is a cross-sectional view taken on the line 3—3 of Fig. 1;

Fig. 4 is a cross-sectional view taken on the line 4—4 of Fig. 1;

Fig. 5 is a cross-sectional view taken on the line 5—5 of Fig. 1;

Fig. 6 is a cross-sectional view similar to Fig. 4, but with the hinge leaves partly open; and

Fig. 7 is a cross-sectional view taken on the line 7—7 of Fig. 3.

Referring to the drawings, the hydraulic checking hinge 21 consists of a casing 11 having a cylindrical cavity and an attached or integral leaf 12, with countersunk screw holes 13 for attaching the leaf to the door frame F. A hinge pin 14 is mounted in the cavity, the hinge pin being pivoted in the bearing 15 in the bottom of the casing 11. A pair of sleeve bearings 16 is provided at the upper end of the cavity, being held in place by the closure bushing 17 which is screw-threaded into the top of the cavity. A rubber-like sealing ring 18 is provided in the space between the ends of the sleeve bearings 16 adapted to prevent any leakage of hydraulic fluid up the hinge pin 14. A reservoir cup 19 is provided in the upper end of the cavity below the closure bushing 17, locking rings 20 and 21 being provided to hold the reservoir cup in position. Below the reservoir cup 19 is provided a segmental partition member or dam 22 whose radial ends form the end walls of a working cham-

ber 23 for the hydraulic piston 24 which is attached to the hinge pin 14 within the working chamber. The segmental partition member or dam 22 is preferably made integrally with the casing 11. The reservoir cup 19 is positioned radially by means of the dowel pin 25 in corresponding holes in the dam and the reservoir cup. The flow of hydraulic liquid from one side of the piston 24 to the other, during the movement of the piston in the working chamber is controlled by variable constricted conduits to give the selected effects upon the door opening and closing. The upper end of the hinge pin 14 is provided with an axial hole 26 in which the metering pin 27 slides, the upper portion of the hole 26 being threaded to receive the threaded portion of the pin 27 and permit adjustment of the position of the metering pin through the knurled end 28 projecting from a cylindrical extension hole 29 in the upper end of the hinge pin. A rubber "O" sealing ring 30 is provided in the groove 31 cut in the metering pin 27. The metering pin near its lower end is provided with a tapered portion 32 where it intersects a hole 33 through the hinge pin 14 leading from one side of the piston 24 to the other. By adjusting the position of the metering pin 27 relative to the hole 33, the hydraulic friction of the hydraulic liquid passing through this hole may be regulated. Also a one-way conduit 34 is provided through the hinge pin 14 within the working chamber 23, this one-way conduit having a seated ball 35 and retainer 36 therefor which permits the liquid to flow freely from one side of the piston to the other, but shuts off the flow when the movement is in the opposite direction.

The reservoir cup 19 is hydraulically connected to the working chamber by two check-valved orifices 37 which permit the hydraulic fluid to flow from the reservoir into the working chamber on either side of the piston but prevent it from flowing in the opposite direction. The hydraulic liquid in the reservoir is non-pressured and in the event that any hydraulic liquid leaks out of the working chamber, it is replenished from the reservoir when a reduced pressure results in the working chamber on one side of the piston from the rotary movement of the piston. The lower surface of the reservoir cup serves as the upper wall of the working chamber 23. This surface

within the working chamber is provided with a groove or grooves of various sizes which affect the hydraulic friction at different angular positions of the piston. As shown, the groove 38 starting from the open position of the hinge is large enough in cross-sectional area so that substantially no hydraulic friction is introduced in the initial movement of the hydraulic piston 24 from the open position of the hinge. As the piston approaches the closed hinge position, a tapered constricted groove 39 is provided for a few degrees of rotation to retard the movement, and as the hinge (and the door) approaches complete closing, the unrestricted groove 40 is provided, so that the energy from a closing force will cause the attached door to close completely into the latch. In the opposite direction of movement of the piston, the hydraulic liquid flows freely through the one-way conduit 34 so that the grooves in the reservoir bottom do not affect the hydraulic friction in the opening direction of movement. As noted above, the reservoir cup 19, including the bottom thereof which serves as a closing wall for the working chamber, is readily removed and replaced by taking out the closure bushing 17 and the locking rings 20 and 21. This arrangement permits changing the reservoir and its grooves 38, 39 and 40, and consequently changing the hydraulic friction or checking effect to any desired position in the cycle, and to any desired amount. Interchangeable reservoir cups with different by-pass grooving may be provided, so that the selected door checking may be had by inserting the proper cup at the time of original installation, or at any subsequent time.

The other leaf 41 which is usually attached to the edge of the door D by screw holes 13, is provided with a split hub member 42 having an axial hole 43 adapted to engage the upper end portion of the hinge pin 14. Clamp screws 44 are provided in the hub member 42 to hold it non-rotatably on the hinge pin 14. A closing cap 45 may be provided to cover the knurled adjusting knob 28 of the metering pin.

I claim:

1. In an hydraulic checking hinge, two hinge leaves, an hydraulic cylinder attached to one of said leaves, a fixed partition defining a segmental working space in said cylinder, a rotary piston in said working space, a shaft for said rotary piston rotating therewith and attached to the other hinge leaf, a closing end wall for said working space adjacent the end sliding surface of said piston, a non-pressured liquid reservoir adjacent said cylinder having one-way conduits to said cylinder adapted at times to deliver hydraulic liquid to one or the other side of said piston, said shaft serving as a hinge pin, grooves in said end closing wall adapted to convey hydraulic liquid with variable degrees of frictional resistance from one side of the piston to an opposite side, whereby to control the resistance to movement of said hinge at selected positions.

2. In an hydraulic checking hinge, two hinge leaves, an hydraulic cylinder attached to one of said leaves, a fixed partition defining a segmental working space in said cylinder, a rotary piston in said working space, a shaft for said rotary piston rotating therewith and attached to the other hinge leaf, an interchangeable liquid reservoir disposed adjacent said cylinder and having its bottom wall forming a piston-contacting surface within said working space, one-way conduits between said reservoir and said cylinder, said one-

way conduits being disposed to at times admit liquid to said cylinder from said reservoir on one or the other side of said piston, said shaft serving as a hinge pin, a one-way liquid passage through said piston adapted to convey fluid from one side of said piston to an opposite side within the working space, and a tapering groove in said bottom wall adapted to by-pass hydraulic liquid around said piston under varying degrees of liquid resistance.

3. In an hydraulic hinge having hinge leaves operating on a hinge pin and a concentric hydraulic cylinder attached to one of said leaves and provided with an internal working space, 15 with a rotary piston movable in said working space; an interchangeable non-pressured liquid reservoir adapted to be placed adjacent said cylinder and forming one wall thereof, one-way conduits between said reservoir and said cylinder, said one-way conduits being adapted to at times admit hydraulic liquid to said cylinder from said reservoir on one or the other side of said piston, the outside face of the wall of said reservoir being provided with groove means disposed in positions to be passed over by said piston, said groove means having varying cross-sectional areas and being adapted to control the hydraulic friction in passing liquid from one side of said piston to the other.

4. In an hydraulic checking hinge having hinge leaves and an hydraulic cylinder and piston arrangement to control the hydraulic friction, a removable interchangeable liquid reservoir adjacent said cylinder, one-way conduits between 35 said reservoir and said cylinder, said one-way conduits being disposed to at times admit liquid to said cylinder from said reservoir on one or the other side of said piston, a one-way fluid passage through said shaft adapted to convey fluid from 40 one side of said piston to an opposite side within the cylinder, and means including a groove having different cross-sectional areas at different positions linearly of said groove in the contact surface between said piston and the bottom of 45 said reservoir, for varying the hydraulic friction in said hinge.

5. In an hydraulic checking hinge having a cylinder, a shaft, a fixed partition, and a rotary piston, with the shaft serving as a hinge pin, a 50 one-way check-valved fluid passage in said shaft adapted to convey fluid from one side of said piston to an opposite side, and means including by-pass grooves in a contact surface passed over by said rotary piston, at least one of said grooves 55 being of tapered conformation to gradually check the movement of said piston in a part of its stroke in the closing direction.

6. In an hydraulic checking hinge having a cylinder, a shaft, a fixed partition, and a rotary piston, with the shaft serving as a hinge pin, a 60 one-way check-valved fluid passage in said shaft adapted to convey fluid from one side of said piston to an opposite side, and by-pass grooves in a removable member constituting a portion of the contact surface passed over by said rotary piston.
